UNITED STATES PATENT OFFICE.

EUGENE L. BARNES, OF WATERTOWN, NEW YORK.

REFRIGERATING APPARATUS.

Application filed May 22, 1925. Serial No. 32,172.

This invention relates to certain new and useful improvements in refrigerating apparatus, and more specifically to a cooler or boiler for such an apparatus.

I aim to provide a simple, convenient, and efficient cooler or boiler for refrigerating systems. The embodiment of my invention here shown and described is particularly adapted for household refrigerating systems, where it may be mounted in the usual ice chamber of an ordinary domestic refrigerator. I also aim to provide against derangement of the refrigerating apparatus by any moisture with which the working substance or refrigerant employed in the system may be contaminated.

Other objects and advantages relate to the details of the structure and the form and relation of the parts of the same, all as will more fully appear from the following description taken in connection with the accompanying drawings, in which:

Figure 1 is a front elevation of the cooler. Figure 2 is a section on line 2—2, Figure 1.

Figure 3 is a section on line 3—3, Figure 1. Figure 4 is a section on line 4—4, Figure 2.

Figure 5 is a view similar to Figure 1 of a slightly modified and perhaps preferred form of apparatus.

The structure here shown is adapted as a whole to be inserted within a refrigerating box, and includes an ice-forming compartment —1— thermoinsulated from the chamber within the refrigerator box (not shown). This ice-forming compartment is provided with its own cooling agency, and means outside of the insulated compartment —1— are provided for cooling the refrigerator box chamber. As here shown, compartment —1— is of rectangular form in horizontal cross-section, with its greater length extending from front to rear. The chamber —1— may consist of two thin spaced sheet metal walls —2— and —3— separated by a layer —4— of any suitable and well known insulation material, such as cork or the like.

As here illustrated, a refrigerant-chamber —5— is mounted and exposed in the interior of the ice-forming compartment —1— at the upper portion thereof, and this chamber —5— may extend throughout the entire length of the compartment —1— from front to rear and may be of a width substantially equal to the interior width of the compartment —1—. It may be supported within

the compartment —1— in any suitable manner, as by securement to the walls thereof. It is shown as filling only a portion of the compartment —1—, with its own lower portion or side freely exposed in the top of the latter, and as leaving a somewhat larger space at the lower part of the compartment which is provided with supporting rods —6— for ice-forming trays —7—. In this particular illustration, three such trays are shown. The chamber —5— constitutes the cooling means or structure for the ice-forming compartment —1—.

Liquid refrigerating medium or refrigerant from any suitable compressor and condenser is supplied thru a pipe —8— to a reserve chamber —9— adapted to contain a reserve quantity of the refrigerating medium. From the chamber —9—, the refrigerating medium, such as ethyl chloride, flows through a downwardly inclined pipe —10— to a chamber or conduit —11— within the chamber —5—, mounted in and secured to the removable front wall —12— of the chamber, and having the form of an elongated tube or cylinder. The pipe —10— preferably enters the chamber —11— at the upper portion of the latter, at the front, as illustrated in Figures 2 and 4. The chamber or conduit 11 is shown of relatively large size in relation to the flow of refrigerant entering from the pipe 10, so as to afford a relatively dead space in its lower portion, below the current of refrigerant at the top, as well as to reduce the general velocity of the refrigerant through the chamber or conduit 11 to a very gentle movement.

For the purpose of controlling the passage of refrigerating medium from the high pressure side of the system to the low pressure side and maintaining a suitable normal level of such medium in said chamber, a float —13— is provided, mounted upon a pivoted rod —14— carrying a valve —15— for controlling a refrigerant outlet —16— at the termination of a downwardly inclined passageway —17— formed in a casting —18— which otherwise closes the rear end of the tube —11—. As shown in Fig. 4, the rear end of the tube —11— around which the casting 18 is mounted has an opening —19— near its upper portion to afford communication between the passageway —17— and the interior of the tube —11—. The float valve may be so arranged as to maintain any normal

level of the liquid refrigerating medium within the chamber 5, preferably substantially such a level as indicated in dotted lines in Figures 2 and 4, so that the refrigerating medium may at all times surround the freezing chamber 11. Any water which may be contained in or carried along by the refrigerating medium collects by gravity in the dead lower portion of the chamber 11, owing partly to the slow movement with which the liquid traverses the relatively large area of the externally immersed chamber 11, and cannot escape through the orifice 19 at the upper portion thereof. Accordingly, such water is frozen in the chamber 11 thereby separated from the refrigerating medium, so that it cannot reach the outlet 16 or come into contact with the valve 15 and thereby interfere with the operation of the apparatus by freezing at such points. The position here shown for the freezing chamber is a preferred one, but it will be obvious that it may be located at any point in the system, in advance of the outlet 16, where the cooling action of the refrigerating medium may effect a separation of the water by freezing the latter.

For the purpose of cooling the refrigerating apparatus chamber which surrounds the compartment 1, additional and separate structures are provided in the form of two similar tube banks arranged upon opposite sides of and spaced from the compartment 1. As here shown, these tube banks include headers 20 and 21, in the form of square tubes extending from front to rear of the structure and of a length substantially equal to the length of the compartment 1 from front to rear. At its upper portion, the header 20 is connected to the trap chamber 5 by means of two spaced tubes or pipes 22, and at its lower portion by a single pipe 23. In like manner, the header 21 is connected at its upper portion to the trap chamber 5 by means of two spaced pipes 24 and at its lower portion by means of a single pipe 25.

As shown, the pipes 22 and the pipes 24 are above the normal level of the liquid refrigerating medium in the trap chamber 5 and in the headers 20 and 21, and serve for returning the vaporized refrigerating medium to the chamber 5. The pipes 23 and 25 are below the normal level of the refrigerating medium in the trap chamber 5 and the headers 20 and 21 serve for supplying the refrigerating medium from the chamber 5 to the headers and to upright cooling tubes 26 and 27 which are connected to the lower sides of the headers and are in direct communication therewith. As shown in Figures 1 and 2, the tubes 26 and 27 terminate in closed lower ends.

Or in a preferred manner as shown in

Figure 5, the tubes 26 may be arranged in an inner and an outer layer and the tubes 27 also arranged in an inner and an outer layer, the tubes of the respective layers being preferably staggered. The outer layer of pipes 26 may be connected to corresponding pipes of the inner layer 27, while the inner layer of pipes 26 may be connected to corresponding pipes of the outer layer 27, producing a U-tube arrangement affording direct communication between the headers 20 and 21.

The structures comprising the headers 20 and 21 and the cooling tubes 26 and 27 serve as means for cooling the refrigerating box 80 chamber which surrounds the compartment 1, being freely exposed to the surrounding atmosphere outside of this compartment. In the tubes and headers the liquid refrigerant absorbs heat and vaporizes, as well as 85 in the chamber or drum 5.

The vaporized ethyl chloride or other gas conveyed to the trap-chamber 5 through pipes 22 and 24 is returned to the compressor (not shown) by a return main 90 40. The trap chamber 5 may be provided with an opening normally closed by a plug 41, through which opening the cooling fluid or refrigerant may be supplied to the cooler and to the system in the amount 95 desired.

Altho I have shown and described a specific construction of cooler as illustrative of a perhaps preferred embodiment of my invention, I do not desire to restrict myself 100 to the details of the structure, or the form and arrangement of the parts thereof, as various changes may be made within the scope of the appended claims.

I claim:

1. A refrigerating apparatus of the character described comprising a cooling compartment, a refrigerant chamber exposed in the interior of said compartment, and vaporizing tubes receiving liquid refrigerant 110 from said chamber exposed to the outside atmosphere at either side of said compartment.

2. A refrigerating apparatus of the character described comprising a cooling compartment, a refrigerant chamber with its lower portion exposed in the top of said compartment, and banks of upright vaporizing tubes receiving liquid refrigerant from 115 said chamber exposed to the outside atmosphere at either side of said compartment.

3. A refrigerating apparatus of the character described comprising a cooling compartment, a refrigerant chamber exposed in the interior of said compartment, and vaporizing structures receiving liquid refrigerant from said chamber exposed to the outside atmosphere at either side of said compartment, said structures comprising headers alongside said chamber and vaporizing 125 130

tubes extending downward from said headers.

4. In an apparatus of the class described, a cooler comprising an ice-forming compartment, a cooling structure for the compartment, an additional cooling structure for the space about said compartment comprising a pair of headers disposed upon opposite sides of said compartment, and cooling tubes connected to said headers.

5. In an apparatus of the class described, a cooling chamber comprising an ice-forming compartment, a chamber for refrigerant within said compartment for cooling the same, a header outside said compartment in communication with the compartment, and a multiplicity of cooling tubes connected to the header.

6. In an apparatus of the class described, a cooler comprising an ice-forming compartment, a trap chamber for refrigerant within said compartment and adapted for cooling the same, valved means within the trap chamber for maintaining a normal level of the cooling fluid in said chamber, and additional cooling structures outside said compartment in communication with said trap chamber.

7. In an apparatus of the class described, a cooler comprising an ice-forming compartment, a trap chamber for refrigerant within said compartment adapted for cooling the same, valved means within the chamber for maintaining a normal level of liquid refrigerant in said chamber, a header outside said compartment, means of communication between the header and the trap chamber at a point below the normal level of the liquid in said chamber, additional means of communication between the header and the trap chamber above the normal level of the liquid in the latter, and a cooling tube in connection with the header.

8. In an apparatus of the class described, a cooler comprising an ice-forming compartment, a trap chamber for refrigerant within said compartment adapted for cooling the same, valved means within the trap chamber for maintaining a normal level of liquid refrigerant in said chamber, an additional cooling structure outside said compartment in communication with said trap chamber, and a freezing chamber in which any water in the refrigerant is frozen before reaching said valved means.

9. In an apparatus of the class described, a cooler comprising an ice-forming compartment, a trap-chamber for refrigerant within said compartment adapted for cooling the same, valved means within the trap chamber for maintaining a normal level of liquid refrigerant in said chamber, a header outside said compartment, means of communication between the header and the trap chamber at a point below the normal level

of the liquid refrigerant in said chamber, additional means of communication between the header and the trap chamber above the normal level of the liquid in the latter, a cooling tube in connection with the header, and a freezing chamber in which any water in the refrigerant is frozen before reaching said valved means.

10. A refrigerating system in which cold is obtained by releasing a liquid medium under pressure and vaporizing it, comprising means for controlling the passage of the medium from the high pressure side of the system to its low pressure side, and a cooler for freezing and segregating any moisture in the high pressure medium, so as to obviate interference with the passage of the medium by freezing of such water, exposed to be cooled by the liquid medium in the low pressure side of the system.

11. A refrigerating system in which cold is obtained by releasing a liquid medium under pressure and vaporizing it, comprising a valve for controlling the passage of the medium from the high pressure side of the system to its low pressure side, and a cooling and settling chamber immersed in the liquid medium at the low pressure side of the valve and traversed by the liquid medium under pressure on its way to the valve.

12. A flooded refrigerating system in which cold is obtained by releasing a liquid medium under pressure and vaporizing it, comprising a chamber for refrigerant at low pressure, valve means for controlling admission of liquid refrigerant from a supply under pressure to said chamber, and a chamber in contact with the liquid medium in said first-mentioned chamber interposed in the supply connection to said valve means and affording dead space for collection of frozen moisture.

13. A flooded refrigerating system in which cold is obtained by releasing a liquid medium under pressure and vaporizing it, comprising a chamber for refrigerant at low pressure, a supply conduit of relatively large size extending into said chamber, and a float valve for controlling the delivery of liquid refrigerant under pressure from said conduit, and maintaining in the chamber a liquid refrigerant level sufficient to substantially submerge the conduit.

14. In an apparatus of the character described, a cooler comprising an ice-forming compartment, a trap chamber for refrigerant arranged within said compartment, ice-forming trays in said compartment, valved means for controlling the flow of liquid refrigerant into the trap chamber, headers disposed upon opposite sides of the compartment, means of communication between the headers and the trap chamber at a point below the normal level of the liquid refrigerant.

- 4
- 5 ant in the latter, additional means of communication between the headers and the trap chamber at a point above the normal level of the liquid within the latter, and cooling tubes in communication with the headers.
- 10 5. In an apparatus of the character described, a cooler comprising an ice-forming compartment, a trap-chamber for refrigerant arranged within said compartment, ice-forming trays in said compartment, valved means for controlling the flow of liquid refrigerant into the trap chamber, headers disposed upon opposite sides of the compartment, means of communication between the headers and the trap chamber at a point below the normal level of the liquid refrigerant in the latter, additional means of communication between the headers and the trap chamber at a point above the normal level of the liquid within the latter, cooling tubes in communication with the headers, and means for freezing any water moving with the liquid refrigerant at a point before the same reaches said valved means.
- 15 6. In an apparatus of the class described, a trap chamber for refrigerant, a pair of headers disposed upon opposite sides of the trap chamber, means of communication between the trap chamber and each of the headers, and a plurality of cooling tubes connected to each header.
- 20 7. In an apparatus of the class described, a trap chamber for refrigerant, a pair of headers disposed upon opposite sides of the trap chamber, means of communication between the trap chamber and each of the headers, a plurality of cooling tubes connected to each header, and a freezing chamber within the trap chamber traversed by the liquid refrigerant on its way to enter the trap chamber.
- 25 8. In an apparatus of the character described, a circulating system for a refrigerant including a trap chamber, headers disposed upon opposite sides of the trap chamber, means of communication between the trap chamber and each of the headers, a plurality of cooling tubes connected to each header, a valve for controlling the level of the refrigerant in the trap chamber, and a freezing chamber in which any water entrained with the refrigerant is frozen before it reaches said valve.
- 30 9. In a refrigerating system in which cold is obtained by releasing a liquid medium under pressure and vaporizing it, the method of preventing moisture in the refrigerant from interfering with passage of the refrigerant from the high pressure side of the system to the low pressure side which comprises exposing the liquid refrigerant in the high pressure side to cooling by the liquid refrigerant in the low pressure side, thereby freezing out and segregating any moisture in the liquid refrigerant in advance of 65 passage of the latter from the high side to the low side.
- 35 10. In a flooded refrigerating system in which cold is obtained by releasing a liquid medium under pressure and vaporizing it, the method of preventing moisture in the refrigerant from interfering with passage of the refrigerant from the high pressure side of the system to the low pressure side which comprises settling and freezing out any 70 moisture in the refrigerant in a dead pocket of liquid refrigerant in the high pressure side of the system; under cooling by the liquid refrigerant in the low pressure side of the system.
- 40 11. In a circulatory refrigerating system an expansion valve opened and closed by a float on the low side of the system dependent upon the level of cold liquid refrigerant; and an ice-forming receptacle through which refrigerant passes to the expansion valve and which is maintained at a water freezing temperature by contact with said cold liquid refrigerant.
- 45 12. In witness whereof I have hereunto set my hand this 12th day of May, 1925.
- EUGENE L. BARNES.
